Attn:

UNITED STATES PATENT OFFICE

160,278

DISPLAY RACK FOR BRUSHES

Lawrence R. Schumann, Boston, Mass., assignor to Star Brush Manufacturing Co., Inc., Boston,
Mass., a corporation of New York

Application December 21, 1949, Serial No. 6,757

Term of patent 14 years

(Cl. D80—10)

To all whom it may concern:

Be it known that I, Lawrence R. Schumann, a citizen of the United States of America, residing at Boston, in the county of Suffolk and Commonwealth of Massachusetts, have invented a new, original, and ornamental Design for Display Rack for Brushes, of which the following is a specification, reference being had to the accompanying drawing, forming a part thereof.

I claim:

The ornamental design for a display rack for brushes, as shown.

LAWRENCE R. SCHUMANN.
